ELECTRON LENS

Otto Klempner, Iver, England, assignor to Electric & Musical Industries Limited, Hayes, Middlesex, England, a company of Great Britain

Application July 29, 1938, Serial No. 221,920
In Great Britain August 4, 1937

7 Claims. (Cl. 250—162)

This invention relates to improvements in or modifications of the electron lenses described in the specification of United States application Serial No. 195,010, filed March 10, 1938.

In the specification of that application an electron lens is described comprising a pair of co-axial cylindrical electrodes the ratio of the effective diameters of which is between 1.5:1 and 2.5:1 and in operation the smaller diameter electrode is arranged to contain the nearly parallel beam of electrons and a higher potential is applied to such electrode compared with the potential that is applied to the other electrode. A lens constructed and operating in this manner is found to provide a focussed beam which is substantially free from spherical aberration over about one-fifth of the diameter of the aperture of the larger diameter electrode. In the preferred form of the invention described in the specification referred to the ratio of the effective diameters of the electrodes is 2:1. In one specific construction the electrodes comprise cylinders of substantially the same diameter and a diaphragm is provided at that end of one cylinder which is adjacent the end of the other cylinder, the diameter of the diaphragm determining the effective diameter of the electrode with which it is associated. As stated above, lenses constructed in accordance with the co-pending application are found to be substantially free from spherical aberration up to about one-fifth of the diameter of the larger electrode.

It is the object of the present invention to provide an improved electron lens in which longitudinal spherical aberration is corrected to a greater extent than in the lenses according to the specification previously referred to.

According to one feature of the present invention an electron lens is provided comprising a pair of co-axial cylindrical electrodes the ratio of the effective diameters of which is between 1.5:1 and 2.5:1 and a source of potential maintaining a potential on one of said electrodes and a substantially different potential on the other of said electrodes, the ratio of the potentials determining the focussing ratio, the smaller electrode containing the nearly parallel beam of electrons and being maintained at the higher potentials, said smaller diameter electrode having a diaphragm which determines its effective diameter, the aperture in said diaphragm being displaced from the end of the electrode with which the diaphragm is associated a distance such that longitudinal spherical aberration is reduced.

According to another feature of the invention

an electron discharge device is provided incorporating a source of electrons, a pair of co-axial cylindrical electrodes adapted to form an electron lens through which a beam of electrons from the source may pass, the ratio of the effective diameters of said electrodes lying between 1.5:1 and 2.5:1, a screen and means whereby different potentials can be applied to said electrodes, the smaller diameter electrode having a diaphragm which determines its effective diameter, the aperture in said diaphragm being displaced from the end of the electrode with which the diaphragm is associated a distance such that spherical aberration is reduced, said screen being so positioned in relation to the electrodes that when a more positive potential is applied to the electrode of smaller diameter the beam is focussed upon said screen when the electrode of smaller diameter is arranged to contain the nearly parallel beam of electrons.

The diaphragm may be a plane diaphragm, the whole diaphragm being displaced from the end of the smaller effective diameter electrode, or alternatively, the diaphragm may be of a substantially frusto-conical or equivalent form which projects into the interior of the smaller effective diameter electrode.

Preferably the actual diameters of the two cylindrical electrodes are the same, but this is not essential, since the diameter of the aperture in the diaphragm determines the effective diameter of the electrode with which it is associated. The ratio of the effective diameters is preferably 2:1. It is found that in lenses constructed in accordance with the invention spherical aberration can be reduced and that a lens can be constructed which is substantially corrected up to about one-quarter of the diameter of the larger electrode.

In order that the said invention may be clearly understood and readily carried into effect, it will now be more fully described with reference to the accompanying drawing in which:

Figure 1 illustrates diagrammatically a lens constructed according to one form of the invention.

Figure 2 illustrates diagrammatically a lens constructed in accordance with another embodiment of the invention, and

Figure 3 illustrates the application of the invention to a cathode ray television transmitting tube.

As shown in Figure 1, the lens comprises a pair of cylindrical electrodes 8 and 9 of substantially the same diameter, the electrode 8 having a plane diaphragm 10, the aperture in the diaphragm de-

termining the effective diameter of the electrode 8, the effective diameter of said electrode being half the effective diameter of the electrode 9. The diaphragm 10, as shown, is displaced from the end of the electrode 8 adjacent the end of the electrode 9 so that its aperture is disposed at a distance from the end of the electrode 8 corresponding approximately to the radius of the larger diameter electrode. In operation the electrode 8 is maintained at a higher potential than the electrode 9 and is arranged to contain the nearly parallel beam of electrons as described in the specification of United States Patent application Serial No. 195,010. The ratio of the potentials applied to the two electrodes determines the focussing ratio. With a lens constructed as described in Figure 1 optimum results have been produced, that is to say, the lens is substantially corrected for longitudinal spherical aberration up to about one-quarter of the diameter of the larger electrode 9. It is found that lenses in which the aperture in the diaphragm is displaced to an extent about one-half of the radius of the larger electrode 9 or twice the radius of that electrode, longitudinal spherical aberration is reduced compared with lenses described in the specification referred to, but for optimum results the aperture in the diaphragm 10 should be displaced a distance corresponding approximately to the radius 30 of the electrode 9, as stated above.

Figure 2 of the drawing illustrates a modified form of the invention in which the diaphragm 10, instead of being of the form shown in Figure 1, is of a frusto-conical shape, the frusto-conical portion projecting into the interior of the electrode 8. The diaphragm is attached to the end of the electrode 8, the frusto-conical portion commencing at a short distance from the periphery of the electrode 8, the semi-angle of the frusto-conical portion being about 45°. The extent to which the aperture in the frusto-conical portion projects into the interior of the electrode 8, i. e., the distance indicated by the arrow 10a in Figure 2, is approximately equal to one-half of the radius 45 of the larger electrode 9. With such a construction the results obtained are substantially the same as those obtained with the arrangement shown in Figure 1. Instead of providing the frusto-conical portion, equivalent configurations 50 may be used, as for example, the inwardly projecting portion of the diaphragm may be a portion of the sphere.

The focussing ratio which determines the focal strength of the lens in practical cases will be determined by the geometry of the electron discharge device to which the lens is applied and hence the potentials applied to the electrodes will be governed by this factor. In practical cases the focussing ratio will probably vary between 2:1 and 8:1.

The electrons may be incident on the high potential side of the lens so as to be decelerated by, and brought to a focus at the low potential side, or may be incident on the low potential side, accelerated by the higher potential electrode to a nearly parallel but converging beam.

The electron lens in accordance with the invention may be applied to any type of cathode ray tube or electron discharge device where found desirable and Figure 3 of the accompanying drawing illustrates a lens in accordance with the invention applied by way of example to a cathode ray picture scanner for use in television transmitting systems. The picture scanner comprises an evacuated envelope 11 of bulbous form hav-

ing a tubular neck 12 in which the lens is arranged. The lens shown is of the kind illustrated in Figure 1 and comprises two equal diameter cylindrical electrodes 8 and 9, the electrode 8 having a diaphragm 10. In the bulbous portion of the tube 11 a photo-sensitive mosaic screen 13 is arranged associated with a conductive signal plate 14. An optical image of a subject for transmission is projected onto the mosaic screen 13 through an optical system indicated generally at 15, projection of the optical image onto the mosaic screen causing the elements to acquire electro-static charges according to the intensity of the picture from point to point. On scanning the mosaic screen by a cathode ray beam the elements of the mosaic screen are restored to a datum potential, restoration of the elements to the datum potential generating currents in the signal plate 14, which are applied to a suitable amplifier from across a resistance 16 connected to the signal plate 14. The electron lens, in accordance with the invention, is employed for the purpose of focussing an electron beam emanating from a cathode 17, such electron beam being employed for scanning the screen 13 and being deflected in known manner by the provision of electrostatic scanning plates or by the provision of electromagnetic scanning coils, not shown. The required potentials for the electrodes 8 and 9 may be derived from tapping points 30 on a potentiometer 18 connected across the poles of a battery. The potentiometer 18 may supply potentials to other electrodes of the picture scanner.

I claim:

1. An electron gun comprising a cathode followed by in the order named, a control electrode in register with the cathode, a first annular cylindrical electrode of predetermined internal diameter in register with both the cathode and control electrode, a second annular cylindrical electrode in register with the first cylindrical electrode, the effective ratio of diameters of said two cylindrical electrodes lying between 1.5 to 1 and 2.5 to 1, an apertured diaphragm within said 40 second cylindrical electrode and positioned at a distance of the order of one half the internal diameter of the first cylindrical electrode from the end of the second cylindrical electrode nearest the first cylindrical electrode, said aperture 45 having a diameter of the order of one half the internal diameter of said first cylindrical electrode to reduce longitudinal spherical aberration.

2. An electron gun comprising a cathode followed by in the order named, a control electrode 55 in register with the cathode, a first annular cylindrical electrode of predetermined internal diameter in register with both the cathode and control electrode, a second annular cylindrical electrode in register with the first cylindrical electrode, said two cylindrical electrodes having substantially the same diameter, an apertured diaphragm within said second cylindrical electrode and positioned at a distance of the order of one half the internal diameter of the first cylindrical 60 electrode from the end of the second cylindrical electrode nearest the first cylindrical electrode, said aperture having a diameter of the order of one half the internal diameter of said first cylindrical 65 electrode to reduce longitudinal spherical aberration.

3. An electron gun comprising a cathode followed by in the order named, a control electrode in register with the cathode, a first annular cylindrical electrode of predetermined internal diam-

eter in register with both the cathode and control electrode, a second annular cylindrical electrode in register with the first cylindrical electrode, the effective ratio of diameters of said two cylindrical electrodes lying between 1.5 to 1 and 2.5 to 1, and an apertured diaphragm within said second cylindrical electrode, said aperture lying in a plane located at a distance of the order of one-half the internal diameter of said first cylindrical electrode from the end of the second cylindrical electrode nearest the first cylindrical electrode, said aperture having a diameter of the order of one-half the internal diameter of the first cylindrical electrode to reduce longitudinal spherical aberration.

4. An electron gun comprising a cathode followed by in the order named, a control electrode in register with the cathode, a first annular cylindrical electrode of predetermined internal diameter in register with both the cathode and control electrode, a second annular cylindrical electrode in register with the first cylindrical electrode, the effective ratio of diameters of said two cylindrical electrodes lying between 1.5 to 1 and 2.5 to 1, and a frusto-conical apertured diaphragm located at the end of the second cylindrical electrode nearest the first cylindrical electrode, the plane of the minimum diameter of the aperture lying at a distance of the order of one-half the internal diameter of the first cylindrical electrode from the end of the second cylindrical electrode to reduce longitudinal spherical aberration.

5. An electron gun comprising a cathode followed by in the order named, a control electrode in register with the cathode, a first annular cylindrical electrode of predetermined internal diameter in register with both the cathode and control electrode, a second annular cylindrical electrode in register with the first cylindrical electrode, said two cylindrical electrodes having substantially the same diameter, and a frusto-conical apertured diaphragm located at the end of the second cylindrical electrode nearest the

first cylindrical electrode, the plane of the minimum diameter of the aperture lying at a distance of the order of one-half the internal diameter of the first cylindrical electrode from the end of the second cylindrical electrode to reduce longitudinal spherical aberration.

6. An electron gun comprising a cathode followed by in the order named, a control electrode in register with the cathode, a first annular cylindrical electrode of predetermined internal diameter in register with both the cathode and control electrode, a second annular cylindrical electrode in register with the first cylindrical electrode, the effective ratio of diameters of said two cylindrical electrodes lying between 1.5 to 1 and 2.5 to 1, and a planar apertured diaphragm within said second cylindrical electrode and positioned at a distance of the order of one-half the internal diameter of the first cylindrical electrode from the end of the second cylindrical electrode nearest the first cylindrical electrode, said planar aperture having a diameter of the order of one-half the internal diameter of said first cylindrical electrode to reduce longitudinal spherical aberration.

7. An electron gun comprising a cathode followed by in the order named, a control electrode in register with the cathode, a first annular cylindrical electrode of predetermined internal diameter in register with both the cathode and control electrode, a second annular cylindrical electrode in register with the first cylindrical electrode, said two cylindrical electrodes having substantially the same diameter, and a planar apertured diaphragm within said second cylindrical electrode and positioned at a distance of the order of one-half the internal diameter of the first cylindrical electrode from the end of the second cylindrical electrode nearest the first cylindrical electrode, said planar aperture having a diameter of the order of one-half the internal diameter of said first cylindrical electrode to reduce longitudinal spherical aberration.
